UNITED STATES PATENT OFFICE.

JOHN T. QUIGLEY, OF BOSTON, MASSACHUSETTS, ASSIGNOR TO COSTMETER COMPANY, OF BOSTON, MASSACHUSETTS, A CORPORATION OF MASSACHUSETTS.

FILING AND INDEXING EQUIPMENT.

1,385,148.

Specification of Letters Patent. Patented July 19, 1921.

Application filed November 2, 1918. Serial No. 260,847.

To all whom it may concern:

Be it known that I, JOHN T. QUIGLEY, a citizen of the United States, and a resident of Boston, in the county of Suffolk and 5 State of Massachusetts, have invented an Improvement in Filing and Indexing Equipments, of which the following description, in connection with the accompanying drawing, is a specification, like characters on the 10 drawings representing like parts.

This invention relates to filing and indexing equipments, of the class in which the identification-bearing margins of the sheets are arranged in overlapping relationship; 15 and is more especially concerned with a sheet and sheet-holder having a novel detachable connection with each other.

My invention will be best understood by reference to the following description, when 20 taken in connection with the accompanying drawings of one specific embodiment thereof, while its scope will be more particularly pointed out in the appended claims.

In the drawings:

25 Figure 1 is a front elevation of a filing and indexing equipment embodying my invention;

Fig. 2 is a front elevation of one of the sheets;

30 Fig. 3 is a rear elevation of one of the sheets;

Fig. 4 is a detail sectional view on an enlarged scale on line 4—4 of Fig. 1; and

35 Fig. 5 is a detail sectional view on an enlarged scale on line 5—5 of Fig. 1, but showing the sheet partially withdrawn from the sheet-holder.

Referring to the drawings, and to the embodiment of my invention which is illustrated therein, I have shown for purposes of exemplification a filing and indexing equipment comprising a plurality of overlapping sheets 10, held by sheet-holders 11, whose 40 terminal portions are mounted in a suitable mounting 12, which may be, and herein is, of common form having inwardly facing flanges 13 overlying the ends of the sheet-holders, and forming channels in which the latter are received. The terminal portions 45 of the sheet-holders are preferably cylindrical, and form trunnions resting on one another, and serving to maintain the overlapping identification-bearing margins of the sheets in properly spaced relationship, while 50 permitting the sheets to be turned about the

axes of their respective sheet-holders, in order to expose either face of the sheet to view. The sheet-holders may be confined in the channels by any suitable upper and lower stops 14 and 15.

In the present example, each sheet-holder 11 is tubular and is provided with a longitudinal slot 16, whose width is such as to receive the sheet and allow the latter to slide longitudinally, yet without undue lateral play. To give the best results, the sheet should fit the slot rather snugly, with only sufficient clearance to permit relative sliding movement of the sheet and sheet-holder. It is desirable that the sheet and sheet-holder shall be normally securely united so that accidental detachment shall be impossible, while still having provision whereby, they may be separated at will when removed from the mounting. It should be understood, of course that the mounting should have suitable provision to permit the sheet-holders to be removed therefrom at will, as by shifting the upper or lower stops. This may be done in a variety of ways, and forms 70 no part of my present invention, which relates to the fastening of the sheets to the sheet-holders.

In the present embodiment of my invention, interlocking connection is provided between the sheet and sheet-holder by the use of one or more, herein a plurality of lateral projections 17, extending from the sheet within the sheet-holder. These projections may be on either or both sides, preferably 75 the latter, and may be formed in a variety of ways. In the present example, they are formed as integral tongues by punching holes 18 which may be, and are herein, arc-shaped, thus forming correspondingly-shaped tongues, which are extruded as best shown in Figs. 4 and 5. Preferably these tongues are formed along a line closely adjacent the slot 16, so that when the inner edge of the card bears against the internal 80 surface of the sheet-holder along a line opposite said slot, there is no substantial play between the sheet and sheet-holder in a direction transversely of the latter. On the other hand, however, the sheet and sheet-holder can be moved freely longitudinally of the sheet-holder, so that when the latter is removed from its mounting, the sheet can be readily removed from and replaced in its 85 holder by relative sliding movement, as well 90

- illustrated in Fig. 5, in which I have shown the sheet partially withdrawn from its holder. Preferably, the slot 16 is provided with rounded or beveled ends, forming diverging walls 19, constituting an entrance to facilitate the introduction of the sheet. The latter may be either single or double, but in the present example, I have shown a folded sheet with the fold inserted in the holder, 5 as clearly shown in Fig. 4.
- Preferably the tongues 17 are formed in pairs, with the tongues of each pair rather closely adjacent to each other, as shown in Figs. 2 and 3, and with one pair adjacent 10 to one corner of the sheet, and another adjacent to the other corner. This arrangement is preferred, as it gives ample stability and provides for the security of the interlocking connection between the sheet and sheet-holder. It should be observed by reference 15 to Fig. 4 that where tongues project from opposite sides of the sheet, the latter in effect has a thickness within the sheet-holder equivalent to three times the thickness of that portion of the sheet which is outside the sheet-holder. It follows that I have thus provided an interlocking connection which 20 possesses great strength and durability, it being impossible to detach the sheet from its holder without first removing the latter 25 from the mounting.
- Having thus described one embodiment of my invention what I claim and desire by Letters Patent to secure is:
1. In a device of the character described, the combination of a tubular sheet-holder provided with a longitudinal slot, and a sheet having a marginal portion extending through said slot to the interior of said sheet-holder where it is provided with projections extending laterally from both faces thereof and locking said sheet against movement transversely out of said slot while permitting the same to slide longitudinally 30 therein.
2. In a device of the character described, the combination of a tubular sheet-holder provided with a longitudinal slot, and a sheet disposed in a plane substantially normal to a plane containing both edges of said slot, said sheet having a marginal portion extending through said slot to the interior of said sheet-holder where it is provided with means projecting laterally from said sheet adjacent said slot and locking said sheet against movement transversely out of said slot while permitting the same to slide longitudinally therein.
3. In a device of the character described, 40 the combination of a tubular sheet-holder provided with a longitudinal slot, and a sheet received in said slot and having its inner edge opposed to the internal surface of said sheet-holder along a line opposite said slot and having means projecting laterally from said sheet within said sheet-holder at a substantial distance from such edge.
4. In a device of the character described, the combination of a tubular sheet-holder provided with a longitudinal slot, and a sheet received in said slot and having projections extending from opposite faces thereof within said sheet-holder.
5. In a device of the character described, the combination of a tubular sheet-holder provided with a longitudinal slot, and a sheet received in said slot and provided with tongues extending in opposite directions within said sheet-holder.
6. In a device of the character described, the combination of a tubular sheet-holder provided with a longitudinal slot, and a sheet received in said slot and provided with one or more tongues relatively narrower than said sheet and projecting laterally therefrom within said sheet-holder.
7. In a device of the character described, the combination of a tubular sheet-holder provided with a longitudinal slot and a sheet received in said slot and provided with a plurality of integral tongues projecting laterally from opposite faces thereof within said sheet-holder.
8. In a device of the character described, the combination of a tubular sheet-holder provided with a longitudinal slot and a sheet received in said slot and provided with an integral tongue formed by punching an opening, said tongue projecting laterally from said sheet within said sheet-holder.
9. In a device of the character described, the combination of a tubular sheet-holder provided with a longitudinal slot symmetrically disposed with reference to the cross-section of said sheet-holder, and a sheet having a marginal portion extending through said slot to the interior of said sheet-holder where it is provided with means projecting laterally from said sheet and locking said sheet against transverse removal from said slot while permitting longitudinal movement therein.
10. In a device of the character described, the combination of a tubular sheet-holder provided with a longitudinal slot, and a sheet having a marginal portion received in said slot and provided interiorly of said sheet-holder with locking means whose thrust is exerted against the internal margin of said slot in a direction substantially normal to a plane containing the edges of said slot and in a direction substantially parallel with the plane of the body of said sheet when a pull on the latter is exerted in an outward direction in its own plane.
- In testimony whereof I have signed my name to this specification.
- JOHN T. QUIGLEY.
